UNITED STATES PATENT OFFICE

171,983

CLOCKCASE

Alan E. Koplar, Chicago, Ill.

Application March 26, 1953, Serial No. 24,209

Term of patent 3½ years

(Cl. D42—7)

To all whom it may concern:

Be it known that I, Alan E. Koplar, a citizen of the United States and a resident of Chicago, in the county of Cook and State of Illinois, have invented a new, original, and ornamental Design for a Clockcase, of which the following is a specification, reference being had to the accompanying drawing forming a part hereof.

In the drawing:

Fig. 1 is a front view of a clockcase, showing my new design;

Fig. 2 is a side view looking at the right hand side of the clockcase as it appears in Fig. 1; and

Fig. 3 is a view taken on line 3—3 of Fig. 1, showing the clock partly as a top plan and partly as a cross section.

The back of the clockcase is plain.

I claim:

The ornamental design for a clockcase, as shown and described.
